UNITED STATES PATENT OFFICE.

RADE N. PEROVICH, OF WASHOE, MONTANA.

RAILWAY SWITCH.

Application filed May 8, 1923. Serial No. 637,535.

To all whom it may concern:

Be it known that I, RADE N. PEROVICH, a citizen of the United States, residing at Washoe, in the county of Carbon and State of Montana, have invented certain new and useful Improvements in Railway Switches, of which the following is a specification.

My invention relates to railway switches and operating mechanisms therefor, and its 10 principal object is to provide a railway switch and operating mechanism wherein the points of the switch may be operated from the train passing the switch from either direction.

15 A further object of the invention is to provide a railway switch operating mechanism embodying elements arranged forwardly and rearwardly of the switch points and connected with the latter and trips carried by the train for engagement with either 20 one of the elements for first setting the switch points and after the train passes the switch engages the other element to return the switch points to inoperative position.

25 Still another object of the invention is to provide a railway switch and operating mechanism therefor which may be installed in any railway and will not necessitate the altering of the switch points and may be installed at a comparatively small cost.

30 With the preceding and other objects and advantages in mind, the invention consists in the novel combination of elements, construction and arrangement of parts and operations to be hereinafter specifically referred to, claimed and illustrated in the accompanying drawing, wherein—

35 Figure 1 is a top plan view of a railway switch embodying my invention.

40 Figure 2 is a transverse sectional view showing a portion of a car.

45 Figure 3 is a detail view of the guide pulley.

Figure 4 is a detail view of the drum and gear.

Referring in detail to the drawing wherein corresponding characters of reference denote corresponding parts throughout the several views, the numeral 5 denotes a rail- 50 way track having a siding 6 and a pair of

pivoted switch points 7 the free ends of which being connected with a transversely shiftable bar 8.

Arranged in advance and rearwardly of the switch points 7 are horizontally arranged gear wheels 9 arranged for longitudinal and rotary movement between oppositely disposed rack bars 10 which are slideable in guides 11 and serve to hold and guide the gears 9 when operated. Drums 10' are 55 fixed to the underface of the gears 9 and engaged about the drums and extended around the same in reverse directions are cables 11' each of which is extended towards the switch points and engaged with pulleys 12 and then extended in divergent relation and attached to the transversely shiftable bar 8 adjacent the ends thereof.

Each of the gears 9 is provided upon its upper face with a pair of right angularly 60 disposed beveled trip engaging members 13, one of each pair of which being normally disposed in the path of a strip 14 depending from a railway car 15. In the operation of the mechanism the parts being in the relative position shown in Fig. 1 the strip 15 engages the switch engaging element to rotate its gear whereby to wind the cable there-around and shift the bar 8 to move the switch points into operative position. After 65 the train passes the switch points the trip engages the switch engaging member of the other gear to rotate the same and wind its cable about the drum and operate the bar 8 into the reverse direction to move the 70 switch points to normal position.

75 From the foregoing it will be seen that I have provided a simple, inexpensive and efficient means for carrying out the objects of the invention, and while I have particularly described the means best adapted to perform the functions set forth, various changes in form, proportion and in the minor details of construction may be resorted to without departing from the spirit 80 or sacrificing any of the principles of the invention.

85 What I claim as new and desire to secure by Letters Patent is:—

The combination with a railway track, a 90

pair of pivoted switch points, of a pair of rotatable elements one of which being arranged in advance of the switch points and the other rearwardly thereof, cables connected with each of the rotatable elements and the switch points and elements carried by the rotatable elements adapted to be en-

gaged by a strip carried by the train to rotate one rotatable element to set the switch points and subsequently rotate the other rotatable element to open the switch points. ¹⁰

In testimony whereof I affix my signature.

RADE N. PEROVICH.
